Plusha Bunker & Friend Udagragoff. Jefferson. Ohio.

Setters Patent

6614X

In addition appears in the Bunker Patent and making part of the same, containing a description to the novelty of the said Plusha Bunker and Jasra Udagragoff. Manner of their improvement in the cooking Stove --

To all whom these presents shall come;

Ist know that in Eliza Bunker's and Jasra Udagragoff of Jefferson County and State of Ohio have invented a new and useful improvement in a cooking Stove and the following is an exact and full description of the said Stove as invented or improved by us.

The invention, within the body of a fireplace, and a fire box even with flues, according to the bottom, top and side walls. These sides are in the form with circular bottoms to be inserted through openings in the top into the top flue, with or without cases, a tube to be placed at the back end, with circulating tubes to be introduced through the back end into the back flue opposite and upon the lower back corner of the oven & a square hollow when desired the oven sides - double fluting placed close to them so open and a double back flue of the heat air passed when closed a sliding gate for double door, with an ash pit to receive the ashes covered with boy & remains, but fastened in the principle of the box, will be inserted with staples and the turner fire cover kept in its place by the side rods of the box, that is to say the bottom extending along the sides & top of the same box to hold the articles intended to be heated or prepared. Consider the openings in the top of the box, how there to receive the bottoms of the flue pipe which are made with edges roundly and polished, for taking, laying, and having a projecting plate on the fire door to complete an open fire place when the door is open and the fire door is closed, and turned to lay down to be fastened at convenient height on the sides.

Let the top be either single

in island cities such as Rio or Salvador as may be preferred. The interior is the
succession of a common tiled floor. There is a doorway with four massive iron
wrought bars. These are held from the corners and supporting them by pillars on the
left and bottom plates, to the side of the feet. In a large, family it may
be three feet long, two feet high and about ten inches wide in the clear. The
fire place opens with the door in the front and screen in the high and narrow
end a half wide. It extends the length and width of the room, and is
eight inches high.

The cover is placed at about an equal distance from each end about 2.5 inches long and 1/2 high exclusive of the thickness of the plates.

The bottom plate rests on ledges on the sides about a yugan and each side only thickness at the end edge. At the top it may be 6 inches shorter. The side plates may be six inches high resting on the ends of the bottom plate in which are ledges running, except to keep the end plates out.

They are further supported on the outside by brackets in the side plates. The top plate of the oven may be made of sheet iron supported on brackets at the sides and bending down to meet the end plates and forming inside of these sides a neck. The doors of the oven are like the side plates and are closed with the bottom, and may also in size and form correspond with the inside of the oven in which case, if the top of the oven be shorter than the bottom, the doors and brackets may extend over the contracted corners.

to the openings in the bone may be made a little lower than the
skin and as long as the bone at top. A little lead on the outside of
the bone plates will give a convenient catch for the crooked thumb. The
hinge may be of very convenient width and the leather be inside of the
bones so that they are protected from passing through and
receiving hair, as many bone holes into spinal bone being made of
the bone drilled out bone cannot be brought with the skin and the
hinge or a wappan clearly remove the pin of the leather made sign for
the purpose and having a drum or key to keep it on.

It may be possible that with trapping from the same of these
birds or other similar species, we may have a high grade of accuracy
in our results as to the date, and in determining the breeding of the species.

than half longer than the doors, the edges of which may be not less than $\frac{1}{2}$ of an inch deep, to support it as conveniently height, the back edge of each door being an inch apart, many courses. These should be longer in the edges of the doors than the thickness of the gate to admit the hands on the under side of the door to make from each corner a flap through to prevent the gate from slipping out of the notches. So if the doors should be as large as the inside of the oven it would project on the edges, the doors will answer. The floor at the bottom of the oven is formed by bottom plate of the oven, and two sliding plates separating it from the back floor except the ventilator hereafter to be described. The bottom sliding plate rests in a notch in a ledge on each side plate, extending from a little back of the back corner of the oven to the front plate. The ledges are half an inch thick and $\frac{1}{2}$ wide. The notch is a $\frac{1}{2}$ inch wide. This back sliding plate reaches forward to the middle of the oven. The front sliding plate laps half an inch on the front edge of this and rests on the upper surface of the ledge and extends to the front corner of the oven, to which are upright bars of the plate reaches. The bottom plate of the oven has a ledge on its under surface at the front end $\frac{3}{8}$ of an inch at its greatest thickness and one inch wide to which the upright bars of the front sliding plate reaches. Each sliding plate has on its under side, near near its front edge a step by which to push it backward or forward, with a poker with a curved iron. At the back end of this floor is a plate running across the oven and meeting with its lower edge in notches in the edges of the sliding plates, so as to close with the back sliding plates, and extending perpendicular half an inch back of the oven and two inches above its lower corner. It is kept from moving forward by the ledges at the back of the oven, and the notches in them of the top floor, and from going back by upright bars on the back plates reaching up as high as the cap of the floor. The top floor is between the top of the oven and the top of the door. The ledges for the top of the door are formed like notches across the top edge, the largest distance between being the door.

On the top of the door there are two iron projections to receive and hold the

182.

The chiminea or chimney on these boilers are for the purpose of the fire.
The sea hole may be made of any casting iron box large enough in the
body to hold the opening designed for it in the top of the stove. The bottom
is to be made of plate iron the same, should be formed in the same manner as the
bottom of the boiler. The design for the one place may be by such a way
as to have the side of the boiler as a rounded at the corner. The bottom
is to be made of the middle opening on the top of the stove should not extend
into the fire more than two inches deep. This should be divided in the bottom
as the other. The openings in top of the stove for boiler &c. are to measure
one $\frac{1}{2}$ inches long, in the direction across the stove, and eight inches wide
the corners rounded as may be desired. The fire at the back end may be
34 inches apart. The opening for the chimney is 14 inches across the stove and
6 inches between it and the opening on each side is a space of 14 inches.
The back of the back end of the stove may be made of wood, or any other
suitable material. In the former case, the side part the stove may be
joined with it, it may be in the form of a bay of convenient dimensions
and when attached to the stove stand in a tenth of convenient height.
It is to have two iron bars of about $1\frac{1}{2}$ inch in diameter made of copper
or other suitable material and bent in the middle so as to bring the straight
parts nearly parallel with each other, about 6 inches apart from each other
and each end of each bar should be fixed so as tightly in the back end of
each as may be necessary for safety and the other end as a post immovable
in the bottom one. When these bars are inserted in the back end of the
stove it should be long enough to admit the back stand, or such stand as
may be used. The holes in the back end of the stove extending through an opening in
the back plate of the stove in the back fire nearly to the back end of the bottom
plate. The opening in the back plate may be seen made from the bottom
one inches high and wide enough to admit the bars. It may be open
or closed as the end may be convenient, the tubes in the boiler they
should pass through a plate of sheet iron or other suitable material
large enough to hold the opening in the end plate and the tubes to
the back end to admit to the bottom of the boiler a space of 14 inches
from the bottom and a space the tubes. Another stand may be made

Further opening taken back to the inner, was fastened by a block at one side and a bolt with a lock on each of the remaining 3 sides.

The bottom plate of the door may be turned out at the sides of the door and 2 inches on each side rounded off in a circular form, or these iron plates may be made and attached to the door.

With former door a rock will pop through these holes. They are designed to support small blocks on the bottom with mounting holes similar in principle to those of the back door, - or to let out from them a rock to keep them at the sides of the door. To admit the sides of the side plates the opening of suitable size may be made in the side plates, and covered with plates suspended by a wire (such) at the upper end and immediately above the opening. If one is used for each case of the door it is without doubt necessary to make to just fit the bottoms of the top plates as just so far as regards to the fire. They should fit the door the closely, and be perforated with a mounting small holes. They will obstruct the action of the fire in some degree, but will defend the door from much of the heat that would collect upon them. On each side are two clasp plates made of thin plates of cast iron sheet weighing enough to counter weight the stone. Without grinding off the ends and sides enough for the rock to close the door, without breaking against each other or the other plates they are fixed on guides over their entire length passing through the side plates and the iron the ends ground to receive a small hole similar to those described for the doors of the rear. The two outer plates where the clasp plates are closed and turn out from each other the clasp plates are opened and raised to stand up against the sides of the door. They should be placed to come down in the floor and not to reach the bottoms of the plates when opened.

In the bottom plate at the front end is an opening through each side plate about three inches long from 1/2 width. They are closed and opened by a stopper or stoppers on the outside of the door, which are suspended on rods which pop through holes of them above at each corner of the door and project inwards to admit them off the door to a short distance so as to give a clear space between the bottom plate and the door and the door and the floor. This is to prevent the door from being closed when the door is closed.

and are adjusted by screws to the right length. These handles of any dimension may be applied to the dampers to cover them back and forward. The white appearance of the wood and short plate to which they are attached, must not be so thick as to the frame or edge of the iron sliding plate to stand them in being pushed back.

The cover to the fire place may be hinged as common and one side may reach to the top, and the other hinged to the first with inside, the pins on which they turn, passing through the doors and covering handles as already described. That hinged to the top may be twisted at one end to an upright bolt of convenient length the upper may which passing thro' a step, covers the top or edge of the door, which will be shot up or down, as the handle is turned.

The bottom of the grate is 24¹/₂ inches long, and 12 inches wide, resting by their edges on the sides of the ash pit and extending forward a quarter of an inch out side of the doors. The back of the wood may be about 14 inches wide at top, diminishing off the points at bottom of 4¹/₂ inches deep, and a quarter of an inch apart for coal they may be wider. At the back end of the grate is a plate attached by hooks (in holes drilled into the end of the grate) 12 inches long, and 5 inches wide to cover the ash pit when the grate is thrown forward. To cover the grate, there must have a front and two sides. The sides are six inches high having a top. The ends on the inner sides have each a square or semi-circular projection in the front of the side of the side grate (taken away the thickness of the top of the side grate) when away the thickness of the door, is 8¹/₂ inches, less the height of the front grate, which is about 4 inches high (leaving 2¹/₂ inches). This when this is all stopped out a dove tail open mortise slanting downward and forward on the outer sides to receive a cross pointing dove tail and when such cross the top bar of the front grate is cut by a hictle the side grates are built together; the bars of the front grate have small tongues, under these these tails to stop them in the grooves in the ends of the side grates.

The back is attached to the bottom by cleavers at the bottom of each side grate standing inward and passing between the two side bars on each side of the bottom grate, wider out to receive them.

To add to another

call with the bottom plate or some of these iron and riveted to it, at his convenience he should be taught on the lines of the ash pit about 16 of an inch thick stone made like a flat brick, down and up and inward which the fire shall never be raised. A white boy to fit this pit and close it at the ground and under the hearth shall make a slide in a cove of the ash pit like a doorway. The fire may of it should be so deep as to reach up to the bottom of the bottom plate, the other part should be so shallow as not to come in contact with the grate. In the bottom plate behind the ash pit is a second ash pit cast 16 inches deep as near as the ash pit and extending back to within 4 inches of the back of the stove.

The openings of the top may be closed when the boilers are out of use for other purposes by covers with edges raised at pleasure and ledge at bottom adapted to the size of the holes in the top. These may be used for baking, &c. Thin plates may be also used to cover these holes, having holes in them adapted to receive small pots &c. to increase the surface of the stove. Together these may be made of tin fitted to the size of the boiler and suspended from the top by strips of tin hooked on the edges of the boiler. The covers for the boilers must be made to open soon for these objects.

A plate of sheet iron about 6 inches wide attached to the front plate on the side and extending across the stove with the ends bent down about one inch. The fire by the use of the dampers may be thrown between back of the stove, and by putting either end of the top plate forward when the stove is put up the fire may be placed near the back of front end. When it is desired to heat the oven to its hottest state there will be sliding plates forward and open the dampers of the front fire.

If the heat is needed particularly in the front end of the oven keep the dampers open and push back both plates. To take off a portion of the heat without the sliding plates do as to exclude the fire from the bottom of them. If it is necessary to add a slide more open the side dampers and let on the cold air into the fire. Place the upper back plate further back to keep open the back dampers as this and push the plates back to make an open fire front only with coal.
